UNITED STATES PATENT OFFICE

SUZANNE BASSEAU, NÉE GUICHARD, OF PARIS, FRANCE

ANTIBACKFIRING GAS MIXER

Application filed December 2, 1930, Serial No. 499,581, and in France December 7, 1929.

The present invention relates to a device for internal-combustion engines, intended to produce a perfectly homogeneous explosive mixture, saving thus fuel, and, at the same time, prevent back firing into the carburetor.

Two embodiments of the device are illustrated on the annexed drawings, where:

Figure 1 represents a perspective view of one of these embodiments,

Figure 2 is a modification thereof,

Figures 3, 4 and 5 are detail views thereof.

These devices may be placed in any convenient point of the path followed by the carburetted mixture.

The device shown in Figure 1 consists substantially in a nozzle 1 inserted in the path of gas supply to the motor and contains a gently friction mounted helical screw 2 the axis 3 of which may freely rotate between two points 4 and 5, fixed for instance on cross pieces 6 and 7 adapted on the ends of the nozzle 1.

On the end of screw 2, facing the carburetor, a spray-device is fixed (8), consisting, as an instance, of a fine wire-gauze disc.

It is easily seen that in consequence of the suction of the engine the gas stream, when getting in contact with the rotating surface 8, will be finely atomized and vigorously stirred up before beginning to flow into the helical space included between the screw 2 and the inside face of the nozzle 1.

The explosive mixture thus finely atomized, follows in its way up this helical space causing the movable system formed by screw 2 and strainer to start rotating, being itself thus still more stirred up permanently by said screw.

Rotation takes place always in the same direction on account of the thread of the screw; it is then clear that in case of firing back into the engine and in order that the carburetor might be reached and set on fire, it would be necessary for the screw to be braked and completely maintained fixed, and be then forced to rotate in an opposite direction to that produced by suction.

No back flow, however violent, would be capable of opposing the running direction, as the working cylinders are maintaining a suction sufficient enough to ensure the rotation of the screw and resist efficaciously any pressure in the opposite direction. Even should the back flow suffice to modify the direction of rotation of the device, when the flame gets in contact with the strainer 8 previously mentioned, the latter, also forced to rotate as explained above, will ensure stopping the flame; besides, at that time, the flame would be cooled and its propagation velocity would practically be reduced to zero.

In the modification shown in Figure 2, the same movable device is met with as well as the same atomizer disc 8, but, in the present case, the helical screw is replaced by one or more winglets or screws 2' suitably inclined, having the same function as the mentioned helical screw 2.

It will of course be possible, for some cases, to combine several movable atomizers with the device 2' formerly mentioned; these atomizers could then, for instance, be placed on both sides of said device.

Preferably, the axis 3 of screw 2 should be hollow and carry in its inside, as shown on Figure 3, a spring 9 bearing by one of its ends against an abutment 10 (Figure 5) and by its other end against a sliding abutment 11 (Figure 4) provided with a slit 12, this slit being crossed by a pin 13, these abutments applying against the above mentioned pins 4 and 5.

It is clear that the spring 8, on pushing the movable abutment 11, will automatically take up the play caused by wear.

It is also to be understood that such device for taking up the play may be realized in any other way, the embodiment represented herein showing no limiting feature.

It will be noted that the suction nozzle may also carry, at its end facing the motor, a stationary or rotating device adapted to atomize the petrol droplets that may come out of the device.

It must also be noted that the helical screw or device 2' might also be placed in

any other convenient point of the driving axis 3; this axis may also be mounted on ball bearings or in any other suitable manner, instead of between points.

5 It is also to be understood that screw 2 may be a simple or multiple one and that its thread as well as its dimensions may vary as desired.

10 It is clear that the strainer 2' may be replaced by any other spraying device, for like operation.

15 It is obvious that the apparatus, object of the present invention, may be constructed in one piece with the induction pipe of the engine.

20 Any other modifications that might be effected are intended to be within the purview of the invention.

I claim:

20 1. A device adapted to be positioned in the upright part of a conduit leading from a carburetor to the cylinders of an internal combustion engine, comprising a cylindrical tubular casing provided with axial bushings 25 at the upper and lower ends thereof, adjustable bearing screws enthreaded in said bushings, means for locking said screws in adjusted positions, a cylindrical tubular member arranged axially in said 30 casing, cylindrical bearing elements positioned in the upper and lower ends of the tubular member, each of said bearing elements being provided with an axial recess adapted to receive the bearing portion of said adjustable screws, each of said cylindrical bearing elements having an aperture extending diametrically therethrough, means extending through openings in the walls of the tubular member and the apertures in the bearing elements for securing the bearing elements to the tubular member, one of said apertures being axially elongated to provide for sliding of the bearing element axially of the tubular member, a coil spring positioned in said tubular member between the bearing elements for 35 resiliently maintaining the bearing elements in engagement with the adjustable screws, an Archimedean screw carried by the tubular member and adapted to completely fill the interior of the tubular casing so that all 40 gases passing therethrough will have to travel through the helical passage between the threads of said screw, and a disc of metallic gauze mounted on the rotatable tubular element and interposed in the path 45 of the gases passing through the tubular casing.

45 per and lower ends of the tubular member, each of said bearing elements being provided with an axial recess adapted to receive the bearing portion of said adjustable screws, each of said cylindrical bearing elements having an aperture extending diametrically therethrough, means extending through openings in the walls of the tubular member and the apertures in the bearing elements for 50 securing the bearing elements to the tubular member, one of said apertures being axially elongated to provide for sliding of the bearing element axially of the tubular member, a coil spring positioned in said tubular member between the bearing elements for 55 resiliently maintaining the bearing elements in engagement with the adjustable screws, an Archimedean screw carried by the tubular member and adapted to completely fill the interior of the tubular casing so that all 60 gases passing therethrough will have to travel through the helical passage between the threads of said screw, and a disc of metallic gauze mounted on the rotatable tubular element and interposed in the path 65 of the gases passing through the tubular casing.

55 In testimony whereof I affix my signature.

SUZANNE BASSEAU, née GUICHARD.

60 2. A device adapted to be positioned in the upright part of a conduit leading from a carburetor to the cylinders of an internal combustion engine, comprising a cylindrical tubular casing provided with axial bushings 65 at the upper and lower ends thereof, adjustable bearing screws enthreaded in said bushings, means for locking said screws in adjusted positions, a cylindrical tubular member arranged axially in said casing, cylindrical bearing elements positioned in the up-
